UNITED STATES PATENT OFFICE

JOHN HUBER, OF ST. LOUIS, AND MEYER ROSENTERTER, OF UNIVERSITY CITY,
MISSOURI

WINDOW AWNING

Application filed August 23, 1926. Serial No. 130,854.

This invention relates to an improvement in awnings and has for its primary object the purpose of providing an awning of the roller type which is simple and inexpensive 5 in its manufacture and in the hanging or mounting thereof.

Another object of the invention is in providing an awning with improved means for rolling and unrolling the awning and for permitting the lower portion of the awning to 10 swing outwardly in a projecting manner.

A further object of the invention is in providing the awning with an improved frame structure which is co-operable with the awning in the raising and lowering operations. 15

Other and further objects will appear in the specification and be specifically pointed out in the appended claims; reference being had to the accompanying drawings, exemplifying the invention, and in which:—

Figure 1 is a perspective view of this improved awning showing it in a lowered position.

Figure 2 is a transverse vertical section 25 taken approximately on the line II—II of Fig. 1.

Figure 3 is an enlarged fragmentary longitudinal section taken on the line III—III of Fig. 2 showing the winding spool for the 30 awning roller and the manner of securing it to the roller.

Referring by numerals to the accompanying drawings, 1 designates a window frame and secured to the upper cross member 2 of said frame are a pair of brackets 3 for the support of the pins 4 of a roller 5, and secured on said roller at one end is an awning fabric 6.

Secured to the window frame 1 is a guiding frame 7, said frame being made of a single material length bent so as to form a pair of vertically disposed guiding legs 8 each having a foot 9 formed at its lower end, and securing means such as 10 pass through each foot for securing the lower end of said legs 40 to the window frame. The upper end of each leg 8 is bent outwardly from the window frame as designated at 11, and extending outwardly from each bent portion 11 is a downwardly extending portion 12, said portions 50 12 parallelling the legs 8 and joining

said portions 12 is a horizontally disposed portion 13, and mounted on said portion 13 is an idle roller 14.

It is to be noted that the guiding legs 8 are disposed a distance away from the window frame 1, the upper ends of said legs being held away from the frame 1 by the securing means 15, whereas the lower ends of said legs 8 are held away from the frame by the bent portion 16 of each leg. 55

Slidably mounted on each leg 8 is a shoe 17, each shoe having a pair of ears 18, and secured between the ears of each shoe by a pin or bolt 19 is a leg 20 of a projecting frame 21, said legs 20 being joined by the horizontally disposed cross portion 22 of the projecting frame 21. 60

Mounted on one end of the roller 5 is a winding spool 23, said spool having a projecting portion 24 formed in the hub thereof 70 for securing the spool to the roller 5. In mounting the spool 23 on the roller 5, the bore of the spool is approximately of the same size or diameter of the reduced portion 24a of the roller, and as the projection 24 is disposed adjacent one side of the roller, the spool when mounted on one end of the roller and forced thereon will cause the projection 24 to bite into the roller 5 which is ordinarily 75 a wooden roller. 80

As aforementioned one end of the awning fabric 6 is secured to the roller 5, whereas the lower end of the awning fabric is secured at 25 to the cross portion 22 of the projecting frame 21, and a tape length 26 is secured 85 to one end to the spool 23 for revolving the roller 5 in a winding direction.

When an awning of this improved character has been secured to a window frame or door frame as described, and it is desired 90 to lift or wind the awning from the positions shown in Figs. 1 and 2, the tape 26 is engaged and pulled, and as one end of the tape is secured to the spool 23, the unwinding of the tape from the spool will cause the 95 roller 5 to turn, thereby rolling up the awning fabric 6, and as the legs 20 of the projecting frame 21 are pivoted at 19 to respective shoes 17, the projecting frame 21 will be 100 swung upwardly to an approximate vertical

position as shown at A in Fig. 2 by reason of the upward pull on the awning fabric 6. As the turning of the roller 5 is continued, the projecting frame 21 will be pulled upwardly therewith, thereby pulling the shoes 17 upwardly and in which the awning fabric 6 will be completely deposited on the roller 5. The awning fabric is held in its rolled or deposited position by wrapping the depending portion of the tape 26 around the securing member 27 which is secured to the window frame 1.

When it is desired to lower the awning fabric 6, the tape 26 is unfastened from the member 27, and the weight of the projecting frame 21 will pull the awning fabric downwardly thereby unrolling the fabric from the roller 5, said frame 21 descending until the shoes 17 of said frame abut the bent portions 16 of the guiding legs 8, and on account of the pins 19 of the shoes 17 being disposed on a vertical plane outwardly of the vertical plane or path in which the awning fabric is unrolled from the roller, the cross portion 22 of the frame 21 will swing outwardly beneath the idle roller 14 of the cross portion 13 of the frame 7 thereby projecting the lower portion of the awning outwardly from the window frame. The awning is then secured in a desired projecting position by tying or wrapping the tape 26 around the securing member 27.

Obviously, if it is desired to lower the awning fabric without any projecting thereof, the awning fabric is secured in position by fastening the tape 26 in the required vertical position and in which the projecting frame 21 will be prevented from swinging outwardly.

40 What we claim is:—

1. An awning comprising a supported roller, an awning fabric secured at one end to said roller, a pulling element wound around said roller for revolving it, a guiding frame comprising a pair of vertically disposed portions each portion being downwardly bent at their upper ends and joined by a transverse portion, and a swinging frame to which the other end of said awning fabric is secured 45 slidably mounted on the vertically disposed portions of said guiding frame, said transverse portion of said guiding frame adapted to be engaged by the awning fabric when said swinging frame is swung outwardly.

55 2. A frame for an awning comprising a pair of vertically disposed legs each leg at its upper end being bent outwardly and downwardly, the downwardly extending portion of each leg being parallel to the vertically extending portion for a distance of its length, and a horizontally extending portion uniting 60 said downwardly extending portions.

3. A one piece frame for an awning comprising a pair of vertically disposed legs each 65 leg at its upper end being bent outwardly

and downwardly, the downwardly extending portion of each leg being parallel to the vertically extending portion for a distance of its length, and a horizontally extending portion uniting said downwardly extending portions.

4. A frame for an awning comprising a pair of vertically disposed legs each leg at its upper end being bent outwardly and downwardly, the downwardly extending portion of each leg being parallel to the vertically extending portion for a distance of its length, a horizontally extending portion uniting said downwardly extending portions, and an idle roller mounted on the horizontal portion.

5. A frame for an awning comprising a pair of vertically disposed legs each leg at its upper end being bent outwardly and downwardly, the downwardly extending portion of each leg being parallel to the vertically extending portion for a distance of its length, and a horizontally extending portion uniting said downwardly extending portions, said vertically extending legs serving as guiding elements for the ends of a projecting awning material frame, said horizontal portion serving as a guiding element for the awning material.

6. A frame for an awning comprising a pair of vertically disposed legs each at its upper end being bent outwardly and downwardly, the downwardly extending portion of each leg being approximately parallel to the vertically extending portion for a distance of its length, an idle roller, and means provided between said downwardly extending portions at their lower ends for the support of said idle roller.

7. A frame for an awning comprising a pair of vertically disposed legs each at its upper end being bent outwardly and downwardly, the downwardly inclining portion of each leg being shorter in length than the vertically extending portion, and a horizontal portion disposed between the lower ends of said downwardly extending portions.

JOHN HUBER.
MEYER ROSENTRETER.
